UNITED STATES PATENT OFFICE

2,185,891

STRAP FASTENER

George J. Gilmore, Chicago, Ill.

Application May 22, 1939, Serial No. 274,909

2 Claims. (Cl. 24—168)

This invention relates to strap fasteners and the main object of my invention is to provide a secure locking means for that end of a strap which is to be held and provides a durable, 5 strong, clamping arrangement, thus assuring against "creepage" of that portion of the strap which is clamped or fastened in place.

One object of my invention is to provide such a strap fastener comprised of two articulately 10 secured members, one of those members adapted to be clamped securely with respect to the other and securely clamping a strap portion therebetween.

A further object of my invention is the provision of means which aid in tightening a strap structure prior to final clamping engagement.

Another object of my invention is the provision of a simple, efficient, practical clamping means which is also economical to manufacture 20 in quantity production.

Other objects and advantages of the invention will become apparent by reference to the accompanying drawing and the ensuing description wherein like numerals are used to designate 25 like parts and in which:

Fig. 1 is a top view of my invention with the strap end portion removed therefrom, showing also in dotted position the top member of the invention when swung on its hinge portion.

Fig. 2 is a cross-sectional view on the line 2—2 of Figure 1.

Fig. 3 is a cross-sectional view on the line 3—3 of Figure 1.

Fig. 4 is a cross-sectional view on the line 35 4—4 of Figure 1.

Fig. 5 is a perspective view of my invention. Referring to the drawing, my invention is generally designated by the numeral 6, and comprises two locking members designated by the 40 numeral 7 and the numeral 8.

The lower member designated 7 is a flat piece of material, metal for example, or any other suitable material, and is provided with a series of hinge portions designated by the numeral 9; in like manner the top member is comprised of a metal plate member or other suitable material which is provided with hinge portions designated 10.

These portions 10 and the hinge portions 9 50 cooperate and register so as to admit the retaining member designated by the numeral 11 to be inserted therethru and permit articulatible motion between the member 7 and the member 8.

The member 8 is provided with an elongated 55 slotted opening designated by the numeral 12,

the object of which will be hereinafter explained, and also a cut out portion designated by the numeral 13, having an arcuate portion designated by the numeral 23.

The lower member 7 is attached to the strap 5 designated by the numeral 18 which may be made up of one or more layers of material in order to insure strength and rigidity, the member 7 being secured thereto by a number of rivets designated by the numeral 21.

The strap portion 22 is narrower than the portion 18 and is connected to the strap portion 18 by riveting or any other suitable manner or method; not indicated on the drawing. The strap portion 22 is of suitable 15 width and thickness to fit into the slot 12 of the member 8.

The strap 18 is provided with a hole designated by the numeral 25, and the locking member 7 is provided with a hole 24 in order to 20 receive the screw designated by the numeral 14, having an enlarged head portion designated by the numeral 15. The body of the screw 14 is adapted to fit snugly within the arcuate recess 25 designated 23.

The open portion designated 13 having the arcuate portion 23 is provided in order to furnish clearance for the wing nut 17, thus enabling the upper locking member 8 to be swung open and to clear the shoulder portion of the 30 wing nut 17; this makes it necessary merely to loosen the wing nut 17 a few turns in order to be able to swing open the hinge 8 when it is desired to open the locking member and remove the strap portion 22 therefrom.

If this opening were not provided it would be necessary to remove the wing nut and screw completely before one would be able to swing the hinge portion.

In operation, when it is desired to take the 40 strap structure and gird it around a certain body member and securely tighten this strap on that body member, the locking member is first opened by loosening the wing nut 17 sufficiently to permit the upper locking member 8 to swing 45 open on its pivot 11, then the strap portion 22 is laced thru the opening designated 12 in the manner shown in the drawing Figure 3.

By virtue of the edges 19 and 20 of the opening 12, it can be seen that the upper portion of the 50 strap is securely held in place especially by two surfaces namely the lower surface of the locking member 8 and the upper surface of the locking member 7, thus clamping the portion 22 securely in place and insuring against "creepage" of any 55

kind by the portion 22 after once clamped in the locking member 6.

When the hinge member is in closed position as shown in Figure 5, the thumb or wing nut 17 is rotated so as to effect a clamping action on the screw bolt 14 and made to exert a locking pressure in engagement with the screw bolt 14. The screw bolt 14 is securely locked in place by the lock-nut 16 and held rigidly in place holding together at the same time the locking member 7 with the strap portion or member 18.

When it is desired to remove the entire strap structure from gripping engagement with a member to which it has been attached, it is necessary to first loosen the wing-nut designated 17 by turning it a sufficient number of turns upwardly, this provides a sufficient clearance for the top member 8 to be swung open, and permits the strap 22 to be removed therefrom thus loosening 20 the holding or grip of the strap.

There is a particular advantage in having the member 8 swing in an articulate manner with reference to the member 7, for when it is placed in open position, and the strap 22 passed thru 25 the opening 12 as indicated in Figure 3, then by swinging the upper member designated by the numeral 8 downwardly into position, a definite and preliminary tightening of the strap takes place before the final clamping action of the pressure exerted by virtue of the wing-nut 17 being brought to bear on the top surface of the member 8 rigidly clamping and locking the strap structure in gripping engagement.

My clamp member may be used also for clamping rope members and for joining ends of cables, or where ropes or cables are spliced. The spliced portion which is the weakest portion may be clamped and held securely in place by the top and bottom clamp members, thus tending to 40 strengthen the weaker or spliced portions.

Altho I have described in succinct terms the

nature of my invention, its objects, and its advantages, and inasmuch as it may be susceptible of various modifications, alterations, and improvements, I reserve the right to all such alterations, modifications, and improvements, which 5 may come within the purview of the accompany drawing and the herein descriptions; my invention to be limited only to the prior art and the subjoined claims.

Having thus revealed my invention what I 10 claim as new and desire to secure by Letters Patent is:

1. A device of the character described comprising, in combination, a strap secured to a clamp, the said clamp comprised of two members, a top 15 member articulately secured to a bottom member, said bottom member rigidly secured to said strap, a screw bolt secured to the said bottom member, a lock-nut securing the said screw bolt in fixed relationship with the said bottom member, the 20 said top member provided with slotted means adapted to hold the free end of said strap, and wing-nut means adapted to clamp the free end of said strap.

2. A device of the character described comprising, in combination, a strap secured to a clamp, the said clamp comprised of two members, a top member articulately secured to a bottom member, the said bottom member rigidly secured to the said strap, a screw bolt secured to the said 30 bottom member, a lock-nut securing the said screw bolt rigidly in place, the said top member provided with slotted means adapted to hold the free end of said strap, the said top member further provided with a notched portion providing 35 clearance for a wing-nut when loosened, and also providing an anchorage portion for engagement with the said wing-nut when tightened, and wing-nut means adapted to clamp the free ends of said strap.

40
GEORGE J. GILMORE.
